UNITED STATES PATENT OFFICE.

PER GEORG CARL LUNDBERG, OF WÄRNAMO, SWEDEN.

PROTECTING ARRANGEMENT FOR CUTTERS AND OTHER ROTARY APPARATUS.

No. 901,458.

Specification of Letters Patent.

Patented Oct. 20, 1908.

Application filed October 21, 1907. Serial No. 398,519.

To all whom it may concern:

Be it known that I, PER GEORG CARL LUNDBERG, a subject of the King of Sweden, factory owner, and residing at Wärnamo, in the 5 Kingdom of Sweden, have invented new and useful Improvements in Protecting Arrangements for Cutters and other Rotary Apparatus, of which the following is a specification.

This invention relates to improvements in 10 guards for rotary cutters such as are used in wood turning shops and the invention has to do with that form of guard which automatically covers the cutting tool when the same is not operating and which is automatically 15 withdrawn from a covering or closing position by the work as the same is advanced to the cutter.

One object of the present invention is to 20 avoid the usual mechanism above the work table for operating the guard and to provide a guard which in itself is disposed below the work table either when in an opening or closing position.

The invention will be more fully described 25 in connection with the accompanying drawings and will be more particularly pointed out and ascertained in and by the appended claims.

In the drawing:—Figure 1, is a longitudinal sectional view of a wood cutting mechanism showing the application thereto of my improved guard, the latter being in an open 30 position. Fig. 2, is a similar view showing the guard in a closed position. Fig. 3 is a 35 plan view with the guard in a closed position.

Like characters of reference designate 40 similar parts throughout the different figures of the drawing.

As shown the device of my invention is applied to a wood turning apparatus which 45 consists of a work table *o* provided with an opening *p* through which a rotary cutting tool *c* projects in a manner to operate upon the work *a* as illustrated in Fig. 1. It will be understood however that I do not wish to be limited to this specific application of my invention as the same is serviceable in connection with many other forms of apparatus.

k designates a guard which as shown is circular and is slidably mounted in guides *k'*. Said guard *k* is disposed in a manner to be operated from beneath the work table and completely close or open the opening *p*, and 55 at all times lies below the work table. As shown a projection *k*² is formed on the guard

k to which projection is pivotally connected a socket *i*. A shaft *d'* is conveniently mounted in hanger *o'* depending from the table *o* and is provided with or carries a hub *d*² on 60 which arms *d*, *e* and *f* are formed. A weight *n* is mounted on the arm or extension *f* and serves to normally maintain the parts in the position shown in Fig. 2. The arm *d* projects through an opening *b* formed in the 65 table *o* which opening *b* is disposed somewhat in advance of the opening *p* so that the arm *d* will be engaged by the work *a* as the latter is advanced toward the cutter *c*. The arm projects into and slidably engages the 70 socket *i* so that when the weighted extension *f* or the arm *d* rotates the shaft *d'* the arm *e* and socket *i* will move the guard *k* into or out of the closing position in accordance 75 with the direction of movement imparted to said shaft *d'*.

As shown in Fig. 3, a plurality of guards *k* is provided and each guard is automatically operated by a device similar to that described in Figs. 1 and 2 for the guard *k* 80 thereof. It will be obvious in this arrangement that if a narrow piece of wood is to be operated upon it may be advanced in alignment with one of the arms *d* so as to engage the same and move one of the guards *k* into 85 an opening position thereby permitting the remaining guards *k* to remain in a closing position so as to prevent injury which might otherwise result from exposing portions of the cutter *c* extending laterally on either 90 side of the work. If a relatively wide piece of wood is to be operated upon a correspondingly greater number of guards *k* will be thrown into an opening position.

Referring to Fig. 2, it will be obvious that 95 as the work is advanced on the table toward the cutter *c* it would first engage the arm *d* and swing the guard *k* into an opening position to expose the cutter *c* and swing the weighted extension into the position shown 100 in Fig. 1. When the end of the work *a* has been advanced forwardly beyond the arm *d* the latter will be released and as soon as the work *a* has passed beyond the opening *p* the weighted extension will swing the guard *k* 105 into a closing position as shown in Fig. 2.

I claim:—

1. A device of the class described comprising in combination, a work table provided with an opening for a cutting tool and a 110 slot located in advance of said opening, a rotary cutting tool projecting through said

opening to engage the work on said table, a circular shield for closing said opening, circular guides for said shield, a socket pivotally mounted on said shield, a shaft mounted beneath said table adjacent said slot, a hub mounted on said shaft and provided with a work actuated arm adapted to project through said slot into the path of said work, said hub having a shield lever longitudinally movable in said socket, and a weighted extension serving to normally throw said shield into a closing position and move said arm into the path of said work.

2. A device of the class described comprising in combination, a work table provided with an opening for a cutting tool and a slot located in advance of said opening, a rotary cutting tool projecting through said opening to engage the work on said table, a circular shield for closing said opening, circular guides for said shield, a socket pivotally mounted on said shield, a shaft mounted beneath said table adjacent said slot, a hub mounted on said shaft and provided with a work actuated arm adapted to project through said slot into the path of the work, said hub having a shield lever longitudinally movable in said socket, and means acting through said hub and serving to normally close said shield and throw said arm into said slot.

3. A device of the class described comprising in combination, a work table provided with an opening for a cutting tool and a slot located in advance of said opening, a movable cutting tool projecting through said opening to engage the work on said table, a shield for completely closing said

opening, said shield lying wholly below said table when in an open position, guides for said shield, a socket mounted on said shield, a shield lever movably connected with said socket, a work actuated arm connected with said lever, and means connected with said arm and lever for completely closing said shield and maintaining said arm in the path of the work.

4. A device of the class described comprising in combination, a work table provided with an opening for a cutting tool, a movable cutting tool projecting through said opening to engage the work on said table, a shield for completely closing said opening, means actuated by the work for moving said shield into a position wholly below said table to open said opening, and means serving to normally throw said shield into a position to completely close said opening.

5. A device of the class described comprising in combination, a work table provided with an opening, a movable cutting tool projecting through said opening to engage the work on said table, a shield for completely closing said opening, automatic means serving to normally throw said shield into a position to completely close said opening, and means actuated by the work for throwing said shield into an open position wholly below said table.

In testimony whereof I affix my signature in presence of two witnesses.

PER GEORG CARL LUNDBERG.
